UNITED STATES PATENT OFFICE.

HARVEY ELLIOTT, OF DETROIT, MICHIGAN, ASSIGNOR, BY DIRECT AND MESNE ASSIGNMENTS, TO PEARL MACHINE COMPANY, OF DETROIT, MICHIGAN, A CORPORATION OF MICHIGAN.

DRIVING AND REVERSING GEARING.

1,101,531.

Specification of Letters Patent.

Patented June 30, 1914.

Application filed February 3, 1913. Serial No. 745,783.

To all whom it may concern:

Be it known that I, HARVEY ELLIOTT, citizen of the United States, residing at Detroit, county of Wayne, State of Michigan, have invented a certain new and useful Improvement in Driving and Reversing Gearing, and declare the following to be a full, clear, and exact description of the same, such as will enable others skilled in the art to which it pertains to make and use the same, reference being had to the accompanying drawings, which form a part of this specification.

My invention relates to a gearless driving and reversing clutch which may be used to advantage in connection with motor boats, hoisting apparatus, or other like installations, as shown in the accompanying drawings and more particularly set forth in the following specification and claims.

The object of my invention is to produce an efficient and inexpensive driving and reversing clutch,—dispensing entirely with the trains of gears usually employed in devices of this character—the construction being such that the driving shaft while rotating in one direction may be coupled with a propeller shaft (for example) in line therewith, to drive a boat forward or to reverse the same as required.

Other advantages and improvements will be hereinafter set forth and more particularly pointed out in the claims.

In the drawings accompanying this specification:—Figure 1 is a horizontal sectional view through the clutch mechanism—with parts in elevation—taken on the parting line of the inclosing case and showing the mechanism coupled to provide for a "forward" movement of the propeller blades (not shown). Fig. 2 is a cross-sectional view on line 2—2 of Fig. 1. Fig. 3 is a side elevation of a detail adjacent to the shifting fork. Fig. 4 is a cross-sectional view on line 4—4 of Fig. 5. Fig. 5 is a horizontal sectional view of a detail with the several rolls of the clutch mechanism in rolling driving contact with the cone carried by the propeller shaft as in "reversing" the propeller blades. Fig. 6 is a cross-sectional view on line 6—6 of Fig. 5. Fig. 7 is a cross-sectional view on line 7—7 of Fig. 1. Fig. 8 is a cross-sectional view of a detail on line 8—8 of Fig. 1, with parts broken away. Fig. 9 is an

end elevation of the device; and Fig. 10 a 55 side elevation of the same.

Referring now to the letters of reference placed upon the drawings:—A indicates a driving shaft journaled at its forward end in a suitable bearing in the inclosing case 60 B, which is divided into two parts longitudinally, and bolted together in line with the driving shaft. The rear end of the shaft A is preferably reduced in diameter and housed in a bushing c inserted in the propeller shaft C, as indicated in Fig. 1 of the drawings.

C' denotes a collar keyed to the propeller shaft in turn bolted to a similar collar carried by the shaft of the propeller blades 70 (not shown).

C² is a disk preferably integral with the propeller shaft to which is bolted an annular cone C³.

c' is a thrust bearing between the shoulder a of the driving shaft and the disk C², and c² is a similar thrust bearing between the collar C' and the projecting hub b of the bearing formed in the inclosing case B to receive the propeller shaft C.

D indicates an annular shaft sleeved on the shaft A provided with a slot at d for the passage of a key A' carried by the shaft A, the slot being of sufficient length to admit of a longitudinal movement of the annular shaft along the shaft A, with which it is caused to rotate by the key A'.

E denotes a cone-shaped ring housed within the cone C³ and keyed as indicated at e to the annular shaft D.

E' is a movable key supported in the wall of the ring E adapted to be thrust outward into a key-way e', provided in the cone C³, through the action of the spring E².

F is a cone, of relatively different taper 95 to the annular cone C³, sleeved on the annular shaft D, and provided with a key-way f to receive the projecting key A' carried by the driving shaft, whereby the cone F is caused to rotate therewith while being 100 adapted for longitudinal movement with respect to the shaft.

F' is a projecting sleeve preferably integral with the cone F, formed with a flange F² channeled to receive the friction rolls 105 G' carried by the shifting fork G. At F² the end of the sleeve F' is given a substantially cone-shaped formation with an annu-

lar recess f' adapted to receive the fingers h of the dogs H . The dogs H are pivoted to the collar I which in turn is carried by the annular shaft D .

5 f^2 is a port in the cone F through which oil may be delivered to the periphery of the annular shaft D upon which the cone F is designed to slide.

10 G^2 indicates a transverse shaft journaled in the frame A to which the shifting fork is keyed.

G^3 is a lever keyed to the shaft G^2 for manually operating it.

15 J denotes a collar pinned to the driving shaft A provided with an inclined flange against which the fingers h' of the dog H bear.

20 K is a helical spring sleeved on the driving shaft A , one end of which bears against the collar J , and the other against the end of the annular shaft D .

25 L indicates a supporting ring provided with ears l pierced for the passage of bolts l' by which the ring is secured to the projecting lugs b' of the inclosing case B .

M denotes an adjustable annular frame or cage sleeve over the cone F and provided with a projecting hub M' extending into the ring L .

30 L' is a set-screw carried by the ring L to secure the hub to the ring, upon releasing which the frame may be adjusted to take up wear.

35 N denotes a plurality of rolls mounted on the shafts N' in turn keyed or pinned to the annular frame M ,—the shafts being free to move along the pins to provide for a slight radial adjustment of the rolls whereby they may be brought into rolling contact 40 with the annular cone. The rolls N are tapered slightly to provide a uniform contacting surface throughout their length with both the inner face of the cone C^3 and the outer face of the cone F , thereby insuring 45 an equal or like speed transmission between the gradually increasing diameter of the cone and the rolls throughout their entire length. n is a bushing on which the rolls rotate.

50 O is a casting bolted to the cone F and provided with an inclined slotted way O' through which projects the spring E^2 engaging the movable key E' .

Having indicated the several parts by reference letters, the construction and operation 55 of my device will be readily understood.

For purposes of description and to more clearly indicate the operation of the device, 60 it is assumed to be employed in connection with a motor boat (not shown), though it is equally well adapted for other installations.

When it is the desire of the operator to 65 drive the motor boat forward, the lever G^3

is manually placed in the position indicated in solid lines in Fig. 1 of the drawings. When in this position, the fingers h of the dogs H , rest in the depression f' formed in the periphery of the cone-shaped portion F^3 of the projecting sleeve F' , the fingers h' bearing upon the inclined flange of the collar J , thereby securing the sleeve against accidental longitudinal movement with respect to the driving shaft A . The movable key E' carried by the cone-shaped ring E is forced outward and into locking relation with the annular cone C^3 through the action of the spring E^2 , placed under increasing tension through the rearward (or right hand) movement of the casting O bolted to the cone F when the lever G^3 is moved to the position indicated:—it being obvious that the tension of the spring is increased due to its sliding up the inclined way formed in the casting. The cone-shaped ring E when brought into impinging relation with the inner face of the annular cone C^3 will rotate the latter, causing the propeller blades to move with the drive shaft or in a "forward" direction. Should the load, however, be sufficient to cause "slipping" between the ring E and the inner face of the cone C^3 , the movable key E' will lock the cone ring E in a positive driving relation with the annular cone C^3 immediately upon the key E' registering with the key-way e' in the cone,—the spring E^2 forcing the key to its seat.

It will now be assumed that it is the desire of the operator to throw the device into a neutral position; *i. e.*, the engine being permitted to run without operating the propeller blades. To accomplish this result, the operating lever G^3 is given a slight movement to the left which serves 100 to unseat the fingers h of the dogs H from the depression f' in the cone-shaped portion F^3 , which action permits the spring K to force the sleeve to the right along the driving shaft A , carrying with it the cone-shaped ring E and at the same time automatically releasing the movable key E' from engagement with the annular cone C^3 ,—it being obvious that the spring E^2 engaging the movable key, being acted upon by the inclined way in the casting O , will serve to withdraw the movable key from its locking engagement with the annular cone when the sleeve F' is forced to the left due to the manual operation of the lever G^3 .

It will now be assumed that it is desired to reverse the direction previously taken by the propeller blades. This result is accomplished by a still further movement of the operating lever G^3 to the left. This action causes the cone F to move to the left sufficiently to force outward the rolls N into impinging contact with the inner face of the annular cone C^3 . The rolls contacting as they do throughout their length with

the cone F, are rotated thereby in an opposite direction to that taken by the cone F, and the driving shaft A,—at the same time driving the annular cone C³—by a rolling 5 contact with its inner face—in the same direction as that taken by the rolls and in an opposite direction to that taken by the driving shaft, thus reversing the movement of the propeller shaft C. It will therefore 10 be obvious that while the driving shaft operates in one direction only, the propeller shaft may be actuated in either direction or remain at rest, as governed by the adjustment of the manually operated lever G³. 15 Attention is directed to the fact that when the lever G³ is again moved to the right,—to the position occupied when driving the boat forward,—the cone-shaped portion F³ of the sleeve F' will cause the dogs H to 20 tilt due to the action of the fingers h bearing thereon while the fingers h', bearing upon the inclined face of the collar J will cause the annular shaft D to move slightly to the left and against the action of the 25 spring K, thereby bringing the cone-shaped ring E, carried by the annular shaft, into impinging relation with the annular cone C³. Upon shifting the lever G³ to the left to either a "neutral" or "reverse" position, 30 the spring K will again become active forcing the annular shaft D to the right, thereby assisting in releasing the cone-shaped ring E from engagement with the annular cone C³.

Having thus described my invention, 35 what I claim is:—

1. In a device of the character described, a supporting frame, a driving shaft journaled therein, a driven shaft in line with the driving shaft, an annular cone carried by 40 the driven shaft, an annular shaft sleeved on the driving shaft keyed to rotate therewith but free to slide thereon, means for sliding the annular shaft on the driving shaft, means carried by the annular shaft 45 adapted to engage the annular cone whereby the latter may be rotated in the same direction as the driving shaft, a cone slideable on the annular shaft and keyed to rotate therewith, a plurality of rolls supported in a suitable frame surrounding the cone, and means for moving the cone longitudinally into driving contact with the rolls and for forcing the rolls into rolling driving 50 contact with the inner face of the annular cone, whereby the driven shaft may be rotated in the opposite direction to that of the driving shaft.

2. In a device of the character described, a supporting frame, a driving shaft journaled therein, a driven shaft, an annular cone carried by the driven shaft, an annular shaft sleeved on the driving shaft keyed to rotate therewith but free to slide thereon, means for sliding the annular shaft on the 55 driving shaft, a cone wheel carried by the

annular shaft adapted to engage the annular cone whereby the latter may be rotated in the same direction as the driving shaft, a cone slideable on the annular shaft and keyed to rotate therewith, a suitable 70 frame surrounding the cone to support a plurality of rolls, a plurality of rolls mounted in said frame adapted to be forced into contact with the annular cone, and means for moving the cone longitudinally into 75 driving contact with the rolls and to force the rolls into rolling driving contact with the inner face of the annular cone whereby the driven shaft may be rotated in the opposite direction to the driving shaft. 80

3. In a device of the character described, a supporting frame, a driving shaft journaled therein, a driven shaft, an annular cone carried by the driven shaft having a slot adapted to receive a movable key, an annular shaft sleeved on the driving shaft keyed to rotate therewith and free to slide thereon, means for sliding the annular shaft on the driving shaft, a cone wheel carried by the annular shaft adapted to engage the 90 annular cone whereby the latter may be rotated in the same direction as the driving shaft, a movable key carried by said cone wheel, means for forcing said key into the slot formed in the annular cone to secure a locking driving engagement between the cone wheel and the annular cone, a cone slideable on the annular shaft and keyed to rotate therewith, a plurality of rolls supported in a suitable frame surrounding the cone, and means for moving the cone longitudinally into driving contact with the rolls and for forcing the rolls into rolling driving contact with the inner face of the annular cone, whereby the driven shaft may be rotated in the opposite direction to that of the driving shaft. 95

4. In a device of the character described, a supporting frame, a driving shaft journaled therein, a driven shaft, an annular cone carried by the driven shaft having a slot to receive a movable locking key, an annular shaft sleeved on the driving shaft keyed to rotate therewith and free to slide thereon, means carried by the annular shaft adapted 100 to engage the annular cone whereby the latter may be rotated in the same direction as the driving shaft, a movable spring actuated key carried by said last named means, 105

a spring for actuating said key, a slideable element on the annular shaft keyed to rotate therewith, manually operated means whereby said slideable element may be longitudinally adjusted with respect to the driving shaft, means carried by said slideable element to engage the spring of the movable key whereby upon the manual operation of said slideable element the tension of the spring may be increased to assist in forcing the key into the slot provided for its 110 115 120 125 130

- reception in the annular cone, and also to withdraw the same therefrom as required.
5. In a device of the character described, a supporting frame, a driving shaft journaled therein, a driven shaft, an annular cone carried by the driven shaft, an annular shaft sleeved on the driving shaft keyed to rotate therewith but free to slide thereon, means for sliding the annular shaft on the driving shaft, means carried by the annular shaft adapted to engage the annular cone whereby the latter may be rotated in the same direction as the driving shaft, a slid-
10 able element on the annular shaft keyed to rotate therewith, a frame surrounding the slidable element to support a plurality of rolls, a plurality of rolls mounted in said frame adapted to be forced by the slidable element into rolling driving contact with the annular cone, whereby the driven shaft may be rotated in the opposite direction to the driving shaft, and manually operated means for longitudinally adjusting the slid-
15 able element.
15. In a device of the character described, a supporting frame, a driving shaft journaled therein, a driven shaft, an annular cone carried by the driven shaft, an annular shaft sleeved on the driving shaft keyed to rotate therewith but free to slide thereon, means for sliding the annular shaft on the driving shaft, means carried by the annular shaft adapted to engage the annular cone whereby the latter may be rotated in the same direction as the driving shaft, a slid-
20 able element on the annular shaft keyed to rotate with the driving shaft, a frame surrounding the slidable element to support a plurality of rolls, a plurality of rolls mounted in said frame adapted to be forced by the slid-
25 able element into rolling driving contact with the inner face of the annular cone, said rolls being slightly cone-shaped in form to provide for an equal or like speed transmission between the rolls and the annular cone throughout the length of the rolls.
25. In a device of the character described, a supporting frame, a driving shaft journaled therein, a driven shaft, an annular cone carried by the driven shaft, an annular shaft sleeved on the driving shaft keyed to rotate therewith but free to slide thereon, means for sliding the annular shaft on the driving shaft, means carried by the annular shaft adapted to engage the annular cone whereby the latter may be rotated in the same direction as the driving shaft, a slid-
30 able element on the annular shaft keyed to rotate therewith, a frame surrounding the slidable element to support a plurality of rolls, a plurality of rolls mounted in said frame adapted to be forced by the slid-
35 able element into rolling driving contact with the inner face of the annular cone, said rolls being slightly cone-shaped in form to provide for an equal or like speed transmission between the rolls and the annular cone throughout the length of the rolls.
35. In a device of the character described, a supporting frame, a driving shaft journaled therein, a driven shaft, an annular cone carried by the driven shaft, an annular shaft sleeved on the driving shaft keyed to rotate therewith but free to slide thereon, means for sliding the annular shaft on the driving shaft, means carried by the annular shaft adapted to engage the annular cone whereby the latter may be rotated in the same direction as the driving shaft, a slid-
40 able element on the annular shaft keyed to rotate therewith, a frame surrounding the slidable element to support a plurality of rolls, a plurality of rolls mounted in said frame adapted to be forced by the slid-
45 able element into rolling driving contact with the annular cone, whereby the driven shaft may be rotated in the opposite direction to the driving shaft, manually operated means for longitudinally adjusting the slidable element, and a locking means carried by the annular shaft to engage said slidable element to secure it against accidental displacement when ad-
justed.
50. 7. In a device of the character described, a supporting frame, a driving shaft journaled therein, a driven shaft, an annular cone carried by the driven shaft, an annular shaft sleeved on the driving shaft keyed to rotate therewith but free to slide thereon, means carried by the annular shaft adapted to engage the annular cone whereby the latter may be rotated in the same direction as the driving shaft, a slidable element on the annular shaft keyed to rotate therewith, a frame to support a plurality of rolls, a plu-
55
60

rality of rolls mounted in said frame adapt-
ed to be forced by the slidable element into rolling driving contact with the annular cone, whereby the driven shaft may be rotated in the opposite direction to the driving shaft, manually operated means for longitudinally adjusting the slidable element, and a locking means consisting of a plurality of tilting dogs carried by the annular shaft adapted to engage the slidable element, and means carried by said driving shaft to maintain said dogs in engagement when ad-
justed.

8. In a device of the character described, a supporting frame, a driving shaft journaled therein, a driven shaft, an annular cone carried by the driven shaft, an annular shaft sleeved on the driving shaft keyed to rotate therewith but free to slide thereon, means for sliding the annular shaft on the driving shaft, means carried by the annular shaft adapted to engage the annular cone whereby the latter may be rotated in the same direction as the driving shaft, a slid-
70 able element on the annular shaft keyed to rotate with the driving shaft, a frame surrounding the slidable element to support a plurality of rolls, a plurality of rolls mounted in said frame adapted to be forced by the slid-
75 able element into rolling driving contact with the inner face of the annular cone, said rolls being slightly cone-shaped in form to provide for an equal or like speed transmission between the rolls and the annular cone throughout the length of the rolls.

9. In a device of the character described, a frame, a driving shaft journaled in the frame, a driven shaft journaled in the frame, a clutch member carried by the driven shaft an annular shaft sleeved on the driving shaft keyed to rotate therewith but free to slide thereon, means carried by the annular shaft adapted to engage said clutch member whereby the latter may be rotated in the same direction as the driving shaft, a slidable member on the annular shaft keyed to rotate therewith, a plurality of rolls supported in surrounding relation to said clutch member, and means for moving said slidable member into driving contact with the rolls and for forcing the rolls into rolling driving contact with the inner face of said clutch member whereby the driven shaft may be rotated in the opposite direction to that of the driving shaft.

In testimony whereof, I sign this specification in the presence of two witnesses.

HARVEY ELLIOTT.
